UNITED STATES PATENT OFFICE.

CARL J. LANDIN, OF BOSTON, MASSACHUSETTS.

TIP-APPLYING MACHINE.

Application filed April 15, 1925. Serial No. 23,255.

The present invention relates to tip applying machines and more particularly to machines for applying tips to the end surfaces of the fabric materials such as belts of the type disclosed in the patent of Martin, No. 1,612,978, dated January 4, 1927.

The object of the present invention is to provide a machine for quickly and economically attaching a strip of material to the end face of a piece of fabric, and more particularly for applying a tip to the type of belt described in the patent above referred to.

With this object in view, the present invention consists in certain novel features of construction, combinations and arrangements of parts hereinafter described and particularly defined in the claims.

In the accompanying drawings illustrating the preferred form of the invention, Fig. 1 is a front elevation of the belt tipping machine; Fig. 2 is a sectional side elevation of the machine shown in Fig. 1; Fig. 3 is a front view partly in section of a portion of the machine on an enlarged scale; Fig. 4 is a detail view showing the operation of the tape feeding means; Fig. 5 is a view similar to Fig. 4 at a different stage in the cycle of operations; Fig. 6 is a sectional detail view of the tape tensioning rolls; Fig. 7 is a detail view showing the operation of applying a tip to the belt; Fig. 8 is a view similar to Fig. 7 at a later point in the cycle of operations; Fig. 9 is a bottom plan view of the tip attaching means; and Fig. 10 is a horizontal sectional view of the machine taken on a line corresponding approximately to the position of the tape feed.

The above mentioned patent discloses a belt consisting of an elastic webbing having a covering of leather surrounding its sides and edges and provided with a strip of leather cemented to the pointed end face of the belt to give a finished appearance to the belt and also to protect the side covering from fraying or loosening upon passing of the end of the belt through the buckle. In order to provide for the automatic attachment of such a tip to the end face of the belt, the illustrated embodiment of the present invention comprises in general three

mechanisms,—a belt gripping mechanism for holding the end portion of the belt, a tip attaching mechanism serving to engage the end face of the belt presented by the gripping mechanism and press a tip of leather tape firmly thereon, and a tape feeding mechanism operating automatically at predetermined intervals to draw a strip of tape across the machine in position to be engaged by the tip attaching mechanism and to be pressed upon the belt. In the illustrated embodiment of the invention, the belt gripping and tip attaching mechanisms are mounted for reciprocating motion toward and from each other, being separated during a portion of the cycle of operations to permit the insertion of a new belt to be tipped and the operation of the feeding mechanism to draw a strip of tape between them, and thereafter approaching each other for engagement of the tip attaching devices with the end face of the belt. The three mechanisms are operated in timed relation by means of suitable cams. The gripping and tip attaching mechanisms are cooperatively arranged so that upon their approach they act to press the tip upon the end face of the belt and also to sever the tape immediately adjacent to the side edges of the belt and flush therewith, thus insuring that the end of the belt is properly covered to give a good appearance and to protect the edges of the leather side covering.

Referring to the drawings, the machine comprises a frame 10 upon which are mounted for reciprocating motion a gripper slide 12 and a tip attaching slide 14. The slide 12 carries a belt gripper constituting the gripping or holding mechanism and indicated generally at 16, and the slide 14 carries the tip attaching mechanism indicated generally at 18. The slides 12 and 14 are reciprocated to bring the gripper 16 and the tip attaching devices 18 toward each other by means of cams 19 and 20, the former cooperating with the gripper slide through a cam roll 21 in the cam groove 22, and the latter serving to actuate the tip attaching slide by means of a cam roll 23 in the groove 24. The studs 25 and 26 connecting the rolls with their respective slides

pass through suitable openings in the frame. The cams are mounted on a cam shaft 27 journaled in the frame and actuated through bevel gears 28 and 29 from a driven pulley 30. The slide 12 moves over the face of the machine frame, and the slide 14 over the slide 12, and both slides move between pairs of blocks 31 and 32, constituting ways for the slides. The slides are confined by plates 33 and 34 bolted to the blocks.

The belt gripper 16 comprises a pair of belt holding blocks 35 carried by T-shaped members 36 adjustably secured to the slide 12. The blocks 35 are formed with grooves 37, as shown in Fig. 10, rounded to conform to the shape of the sides of the belt and separated a distance equal to the width of the belt in order that the belt may be accurately positioned for presentation to the tip applying devices. Each block is formed with an inclined groove 38 in its upper face, which serves as a guide for the tape. Secured to the slide 12 is a plate 39 upon which is attached a box-shaped belt guide 40 serving to receive the belt and guide it to the blocks 35. The belt is retained within the gripper by means of a gripper plate 42 which is spring-pressed toward the belt by means of a spring 44 received in a spring cup 46, which in turn is received in openings in the slide 12 and the plate 39. The spring cup 46 cooperates with a cam plate 48 on the frame having a cam surface which is adapted to force the gripper plate against the belt with increased pressure as the slide is moved up. The gripper is retained in position by a ledge 49 formed thereon and overlying the box 40, and a pair of lugs 50 struck up from the bottom of the plate and received in suitable openings in the box 40. The belt, which is indicated at 54 in Fig. 3, is inserted in the gripper when the slide 12 is at the bottom of its stroke, the spring pressure being at this time sufficiently small to permit ready insertion of the belt, while upon the start of the upward movement of the slide the spring pressure is increased to prevent accidental displacement of the belt. The belt is accurately positioned in the gripper by means of a positioning dog 56 having a tail 58 against which a corner of the gripper abuts when the latter is at the bottom of its stroke. The dog has an upward projection 60 bearing against the edge of one of the blocks 35, and the surface of the projection is such as to determine the proper position of the belt within the gripper, as shown in Fig. 3. Upon upward movement of the gripper slide the dog 56 is thrown in a counter-clockwise direction so as not to interfere with the motion of the slide, and upon the return movement the engagement of the gripper with the tail 58 returns the dog to its original position.

65 The tip attaching mechanism 18 consists

of a presser 62 adjustably attached by screws 63 to the slide 14 in a position directly above and in the plane of the belt. The presser has at its lower end inclined surfaces 64 conforming to the pointed end of the belt to adapt it to engage accurately with the pointed end of the belt to press the tip thereon as the gripper and presser are moved toward each other. The presser is of such size and shape as to be received in the grooves 37 of the belt holding blocks after the tip has been pressed upon the end of the belt, the sides of the presser being rounded, as indicated at 65 in Fig. 9, to conform to the shape of the grooves to form shear surfaces between which the tape is cut adjacent the edges of the belt. Cooperating with the presser are two belt guides indicated generally at 66 and 68 for stiffening the belt and maintaining it against sidewise flexure while the tip is being applied, the former constituting a tip guide adapted to engage with the central portion of the end of the belt, and the latter constituting an edge guide to engage with the edge portions of the belt. The tip guide 66 is only of sufficient width to engage the central portion of the belt and comprises a back plate 70 slidably received in a recess 72 in the slide 14 and connected by a lug 74 with a short front plate 76. The lug 74 lies in the plane of the presser and the plates 70 and 76 are adapted to embrace the tip end of the belt, the lower ends of the plates being beveled, as shown in Fig. 2, to insure engagement of the belt between the plates as the slides are brought toward each other. The lug 74 has a triangular notch 78 in its lower end to position the pointed end of the belt. The guide 66 is yieldingly mounted on the slide by means of a pin 80 secured to the back plate 70 and extending through a slot in the slide 14 to be pressed downwardly by a spring 82 received in an opening in the slide. The guide thus has provision for movement relative to the presser, the latter having a recess 84 to accommodate the lug 74 when the guide is moved. The edge guide 68 which serves also as a guide for the lower end of the presser consists of a plate having depending side portions 86 engaging the front surface of the presser and terminating flush with the lower pointed ends of the presser, the portions 86 being formed with blocks 88 similar in form to the belt holding blocks 35 and embracing and conforming to the sides of the presser as shown in Fig. 9. The blocks 88 are provided with tape guiding grooves 90 in their under surfaces. The guide 68 is mounted for free sliding movement with respect to slide 14, for which purpose it has a reduced portion 92 received between the screws 63, and its upper end is provided with a slot 94 within which is received the shank of a screw 96 secured to the slide 14.

The operation of the above mentioned parts is described as follows: In the position shown in Figs. 1 and 2, a tipping operation has just been completed, the slides having been returned to their original positions. At this time the cams 19 and 20 have arrived at a dwell portion with relation to their respective rolls, this dwell portion extending through approximately 180°. During this time, the completed belt is removed from the gripper, and a new belt with the side covering attached but without a tip is placed within the gripper, its pointed face engaging with the positioning dog 56. The end face of the belt is preferably provided with a coating of cement; also during this dwell period a strip of tape cemented on one side is drawn across the machine between the gripper and the tip attaching devices directly above and in alignment with the end face of the belt by means of automatic devices presently to be described in detail. After this 180° dwell rotation, the actuating portions A and B of the cam grooves 22 and 24, respectively, arrive at a position to raise the slide 12 and depress the slide 14 through their corresponding cam rolls. As will be apparent from Fig. 2, the actuating portion B of the cam groove 24 serves to complete the movement of the slide 14 within a relatively few degrees of rotation of the cam shaft, while the portion A of the cam groove 22 acts through a rotation of approximately 90° to effect the complete movement of the gripper slide. The movement of the slide 14 is such as to bring the belt end guide 66 into a position to embrace the tape, the gripper slide having been moved during this period sufficiently so that the end of the belt is received between the plates 70 and 76 of the guide. The guide 68 comes to a position such that its lower end is slightly above the line of the tape. Continued upward motion of the slide 12 causes the tape to be engaged between the pointed end of the belt and the lug 74, and the guide 66 is pushed upwardly against the spring 82, the lug being received in the recess 84 of the presser. The position of the parts at this time is illustrated in Fig. 7, the tape being engaged at its center by the lug 74 and running over the ends of the presser. Further upward motion of the gripper slide brings the tape into engagement with the presser, so that owing to the conformity of the presser to the shape of the belt end the tape is firmly pressed upon the end face of the belt. During this time the side edges of the belt are engaged by the lower portions of the guide 68. The cams 19 and 20 are so arranged that at the limit of the upward movement of the gripper slide the belt will have been depressed through the gripper by the action of the presser thereon, as shown in Fig. 8. The edges of the presser

extend into the guide blocks 35 of the gripper, and because of the conformity of the presser to the shape of the grooves 37 the tape is severed immediately adjacent to the side edges of the belt, the presser having been effective during this entire operation to force the tape firmly upon the end of the belt. It will be seen that the belt edge guide 68 serves also as a guide for the presser, presenting the lower end thereof accurately for admission into the guide blocks 35 of the gripper. Prior to the entrance of the presser into the guide blocks 35, the latter engage the lower ends of the plate 68, thus lifting the guide so that it does not interfere with the cutting operation. As will be observed from Fig. 2, the cams now arrive at a position to move the slides 12 and 14 to their original positions in readiness for another cycle of operations as above described.

The tape feeding means is described as follows: The tape 102 of a width equal to the thickness of the belt and cemented on its under side is wound upon a drum 104 and leads through a pair of tensioning rolls 106 and a pair of tape presenting rolls 108 in position to be engaged by a pair of feeding fingers to be drawn across the front of the machine. As shown in Fig. 6, the rolls 106 are of a form to engage and guide the tape, the upper roll being formed with a groove within which the tape is positioned by the periphery of the lower roll. The upper roll is pivoted on a bracket 110 attached to the frame of the machine, and the lower roll is mounted for rotation on an arm 111 having a hub 112 loosely mounted on a stud 113 journaled in a boss 114 of the frame, the lower roll being urged toward the upper roll by means of a counterweight 116 connected with the hub 112. The tape presenting rolls 108 are of the same form as the rolls 106 and are mounted on arms 118 and 120, the former being secured to the stud 113 and the latter to a similar stud 122 journaled in the boss 114. The arms 118 and 120 are operatively connected together through gears 124 and 126 on the studs 113 and 122 respectively, the arms being urged together in a position to cause the rolls 108 to grip the tape by means of a tension spring 128 taking between the upper arm 120 and a fixed part of the machine. The tape as presented by the rolls 106 and 108 is adapted to be engaged by a pair of feeding rolls 130 of similar form to the above mentioned rolls and mounted upon feeding fingers 132 and 134. The fingers are pivoted at 136 and 138 respectively upon a cross slide 140, which is mounted for reciprocatory movement in ways 142 of the machine. Secured to the studs 136 and 138 are gears 144 and 146 which operatively connect the feeding fingers 132 and 134 together, the fingers 130

normally being urged toward closed position by a tension spring 148 connected between them. The slide 140 is reciprocated to move the feeding fingers back and forth across the front of the machine by means of a lever 150 having a forked end engaging a pin 152 on the slide, the arm 150 being connected through a rock shaft 154 and an arm 156 to a cam roll 158 received in the cam groove 22 of the cam 19 at a point diametrically opposite from the gripper slide actuating roll 21, so that the feeding fingers are reciprocated when the gripper slide is stationary, and vice versa. The feeding rolls 130 are adapted to engage the tape at a point between the rolls 106 and 108, as shown in Fig. 4, and for this purpose it is necessary to separate the rolls 130 to clear the rolls 108 upon a left-hand movement of the cross slide 140 and to separate the rolls 108 to permit the rolls 130 to pass therethrough upon a right-hand movement of the slide. It will be observed from Fig. 10 that the rolls 108 project forwardly from their arms 118 and 120, while the rolls 130 are mounted on the rear side of their respective feeding fingers, so that there is no interference between the arms and the feeding fingers during the feeding operation. In order to provide for the opening and closing of the feeding fingers, a vertical reciprocating slide 160 is mounted on the machine frame between the blocks 32 and a pair of blocks 162. The slide has a bracket 164 (Fig. 2) carrying a cam roll 166 received within the groove 168 of a cam 170 mounted on the cam shaft 26 between the cams 19 and 20. At its lower end the slide 160 is provided with a groove 171 to receive a tongue 172 of a bracket 174 upon which are mounted a pair of studs 175 carrying finger separating rollers 176 engaging opposite sides of the lower feeding finger 134. The upper surface of the bracket 174 is adapted under certain conditions to abut against a shoulder 178 formed on the slide at the upper end of the groove 171. Received in a similar groove 180 of the slide is a tongue 182 of a bracket 184, which at its lower end has a lug 186 adapted to engage the lower surface of the bracket 174. The bracket 184 is urged upwardly by a heavy coil spring 188 connected between screws 190 and 192 attached to the slide 160 and the bracket 184 respectively. Referring to Fig. 2, the arrangement is such that when the cross slide 140 is completing its left-hand movement through the actuation of the cam roll 158 by the portion A of the groove 20 the cam roll 166 engages a portion C of the groove 168 to depress the slide 160, this action, of course, taking place while the slides 12 and 14 are separated. Upon depression of the slide 160, engagement of the shoulder 178 with the bracket

174 causes the rollers 176 to be moved downwardly so as to separate the feeding fingers 132 and 134 by virtue of their connection through the gears 144 and 146. At the limit of the left-hand movement of the feeding fingers, the cam groove 168 arrives at a steep portion D with relation to its cam roll to retract the slide 160 in order that the rolls 130 may close upon the tape through the action of the tension spring 148. The steep portion of the cam groove is extended to a point indicated at E to retract the slide 160 slightly above its original position to place a tension on the heavy spring 188 in order that the projection 186 may be forced against the bracket 174 with a yielding pressure to close the rolls 130 firmly upon the tape while the slide 140 is being moved in a right-hand direction to draw the tape across the machine. At the limit of the right-hand movement of the feeding fingers the additional pressure brought to bear by the spring 188 is relieved by a declining portion F of the cam groove which moves the slide 160 downward to its original position. Upon the right-hand movement of the feeding fingers, rotation of the rolls 130 is prevented by means of a ratchet wheel 204 secured for rotation with the lower roll and engaging with a pawl 206 pivoted on the lower feeding arm and urged toward the ratchet by a torsion spring 207. At the limit of the feeding movement, the pawl is removed from engagement with the ratchet through the engagement of the tail 208 of the pawl with the stud 175 upon which the upper separating roller 176 is mounted. In order to provide for the separation of the tape-presenting rolls 108 upon the feeding movement of the feeding fingers, a cam follower arm 210 is secured upon the inner end of the stud 122 and carries a cam roll 212 adapted to engage with a cam 214 secured on the periphery of the bevel gear 28. Immediately after the closing of the rolls 130 upon the tape, the cam 214 lifts the arm 210 so that the rolls 108 are separated through the connection of their respective arms through the gears 124 and 126. After the feeding fingers have been moved sufficiently to the right to clear the rolls 108, as illustrated in Fig. 5, the latter are again closed on the tape by the action of the tension spring 128, which is assisted in its closing movement by a cam 216 secured to the under surface of the cam 20 and adapted to engage the roll 212. It will be seen that prior to the feeding movement, the tape is positively held between the rolls 106 and 108 for presentation to the feeding fingers, and furthermore that the tape is always engaged either by the rolls 108 or the rolls 130. Moreover, immediately after the start of the feeding movement of the rolls 130 the rolls 108 close on the tape to position the

tape properly in the path of the gripper and tip applying devices.

During the tip applying operation, owing to the pointed end of the belt, it is desirable that the tension on the tape be relieved in order to provide slack tape which may draw freely over the edges of the presser. For this purpose, the tape drum 104 is mounted on a bell crank lever 218 pivoted to the machine frame, the tail of the lever being in the path of a pin 220 attached to the gripper slide 12, so that upon upward movement of the gripper slide the tape drum is swung to the right, as viewed in Fig. 1, to slacken the tape. Upon return of the gripper slide, the bell crank lever and the tape drum are returned to their original positions by means of a spring 222 connected between the bell crank lever and the machine frame which serves to pull the bell crank against a stop 224 projecting from the frame. This permits the tape to draw freely from the left through the rolls 106 and 108. The tape also draws freely from the right-hand side through the rolls 130, the additional pressure due to the spring 188 having at this time been removed and the pawl 206 being out of engagement with the ratchet 204.

It will be observed from Fig. 8 that a short length of tape remains between the rolls 130 after the tape has been severed. In order to eject this tape from the rolls, a rack 228 having a series of ratchet engaging teeth 230 is pivoted at 232 upon the bracket 174 and placed in such a position as to engage with the teeth of the ratchet 204, so that upon a left-hand movement of the feeding fingers the ratchet will be rotated in such a direction as to eject the tape from between the rolls 130. The teeth of the ratchet are so arranged as to pass freely under the pawl at this time. This ejecting operation takes place immediately prior to the separating of the feeding fingers. Upon a feeding movement of the feeding fingers, that is a right-hand movement, viewing the machine from the front, the engagement of the rack and ratchet is such as to cause no rotation of the ratchet which is now restrained by the pawl 206. The right-hand under surface of the rack, which engages with the ratchet at the limit of the feeding stroke of the fingers is made smooth, as shown at 236, in order that the rotation of the rolls 130 to draw slack tape to the pointed end of the belt during the tip applying operation will not be impeded by the rack.

Briefly reviewing the operation of the machine, it will be seen that with the parts in the position shown in Fig. 1 a tipping operation has just been completed and the finished belt is ready for removal from the gripper. A new belt with the side cover-

ing attached and ready for application of a tip is placed in the gripper to be positioned by the positioning dog 56. At this time the gripper and tip applying slides are separated and are motionless for a period of 180° rotation of the cam shaft. During this dwell period, the cross slide 140 is actuated to move the feeding fingers to the left, the fingers being opened by their connections through the slide 160 near the completion of the left-hand movement, in order to clear the rolls 108 so that the tape feeding rolls may close upon the tape held between the pairs of tensioning and presenting rolls 106 and 108. Upon closing of the feeding rolls on the tape, additional pressure is brought to bear by virtue of the heavy coil spring 188, and the cross slide starts on its right-hand movement, the rolls 108 opening at this time to permit the feeding rolls to pass therethrough and closing immediately after the passage of the feeding rolls. At the limit of the feeding movement of the rolls 130, the additional pressure of the spring 188 is relieved, permitting slack tape to draw through the rolls when the end of the belt engages with the tape, as has been described. The slides 12 and 14 are now reciprocated to bring the belt and the presser toward each other, and the tape is pressed upon the end face of the belt and subsequently cut adjacent to the edges of the belt by the cooperation of the presser with the belt holding blocks of the gripper. During the reciprocation of the slides, the tape drum is moved to slacken the tape by the cooperation of the pin 220 with the bell crank 218 so that the tape may draw freely through the pairs of rolls 106 and 108 to be pressed upon the pointed end of the belt. The slides are then retracted to their original position, and the parts are ready for the performance of a similar cycle of operations upon another belt. It will be seen that by the formation of the presser to conform to the pointed end of the belt and also by virtue of the positive guiding of the tape between the presser and the gripper, the tip will be accurately laid on the end face of the belt, thus giving a finished appearance to the belt and also protecting the end from fraying or pulling away from the internal fabric.

I claim:

1. A tip applying machine comprising fabric holding means for holding a flexible strip of fabric, means for pressing a tip against the end face of the fabric, and means for maintaining the fabric against sidewise flexure during the pressing operation.

2. A tip applying machine comprising fabric holding means for holding a flexible strip of fabric, a presser adapted to engage the end of the fabric for applying a tip to the end face thereof, and means for main-

taining the fabric against sidewise flexure during the pressing operation.

3. A tip applying machine comprising means for holding a flexible piece of fabric, a presser conforming to the end of the piece of fabric and adapted to engage therewith for pressing a tip against the end face of the fabric, and means for maintaining the fabric against sidewise flexure during the 10 pressing operation.

4. A belt tipping machine comprising means for holding a belt, tip applying devices including a presser adapted to engage the end face of the belt, means for presenting 15 a strip of tape to be pressed against the end of the belt, and means for cutting the tape adjacent the side edges of the belt.

5. A belt tipping machine comprising means for holding a belt, means for presenting 20 a strip of tape across the end face of the belt, means for pressing the tape against the end face of the belt to cause it to adhere thereto, and means cooperating with the pressing means for cutting the tape adjacent 25 the edges of the belt.

6. A belt tipping machine comprising a holder for the belt, means for presenting a strip of tape along the end face of the belt, and a presser adapted to engage with the 30 tape to press it against the end face of the belt to cause it to adhere thereto and adapted to cooperate with the belt holder to cut the tape adjacent the edges of the belt.

7. A belt tipping machine comprising a 35 belt gripper, means for reciprocating the gripper, means for presenting a strip of tape in the path of the gripper to be engaged by the end face of the belt, means for pressing the tape upon the end face of the belt, and means for maintaining the belt against side- 40 wise flexure during the pressing operation.

8. A belt tipping machine comprising a belt gripper, a presser adapted to engage with the end face of a belt held by the gripper, means for reciprocating the presser, means for presenting a strip of tape in the 45 path of the presser to be pressed upon the end face of the belt by the presser, and means for maintaining the belt against side- 50 wise flexure during the pressing operation.

9. A belt tipping machine comprising a belt gripper adapted to hold a belt, a presser adapted to engage with the end face of the belt, slides upon which the gripper and 55 presser are mounted for reciprocating movement toward each other, means for presenting a strip of tape to be engaged by the presser and laid over the end face of the belt, and means for reciprocating the slides 60 to cause the presser to engage with the end of the belt and thereafter to permit relative movement between the presser and the gripper to cut the tape adjacent the side edges of the belt.

65 10. A belt tipping machine comprising a

belt gripper having guide blocks adapted to engage and conform to the edges of a belt adjacent the end portion thereof, tape feeding means, and means for pressing the tape upon the end face of a belt presented by the 70 gripper.

11. A belt tipping machine comprising belt holding means, means for gripping the belt in the belt holding means, means for reciprocating the belt holding means, means 75 for increasing the gripping pressure upon the belt when the holding means is reciprocated, and means for applying a tip to the belt when the holding means is moved.

12. A belt tipping machine comprising belt holding means adapted for reciprocating movement, means for applying spring pressure against the belt, means for increasing the spring pressure against the belt when the holding means is moved, and a presser 85 for applying a tip to the end face of the belt.

13. A belt tipping machine comprising a belt gripper including a plate adapted to bear against the belt, a spring bearing 90 against the plate, means for reciprocating the gripper, a presser for applying a tip to the end face of the belt, and a cam cooperating with the spring for increasing the pressure of the plate on the belt when the gripper is moved.

14. A belt tipping machine comprising a belt gripper adapted to hold the end portion of a belt, tape feeding means, tape applying means for pressing the tape upon the end 100 face of the belt, a positioning member for the belt gripper adapted to be engaged by the end face of the belt and having provision for movement out of the path of the gripper when the latter is reciprocated, and means 105 for reciprocating the gripper.

15. A belt tipping machine comprising tip applying means, a belt gripper adapted to receive a belt to present the end portion thereof to the tip applying means, means for reciprocating the gripper, and a positioning 110 dog pivoted on the machine and having a face adapted to engage the end face of the belt to determine the position of the belt in the gripper, the dog having a portion abutting 115 against the gripper.

16. A belt tipping machine comprising a belt gripper adapted to receive the end portion of a belt, a presser adapted to engage with the end face of the belt, means for presenting a strip of tape to be engaged by the 120 end face of the belt, and a belt edge guide adapted for free sliding movement relative to the presser.

17. A belt tipping machine comprising a belt gripper adapted to hold the end portion of a belt, a presser adapted to engage the end face of the belt, means for actuating the gripper and presser to bring the presser into engagement with the belt, means for 125 130

feeding a strip of tape between the end of the belt and the presser to be laid on the end face of the belt by the presser, and a belt edge guide adapted to engage with and embrace a portion of the edge of the belt prior to the engagement of the presser therewith to stiffen and guide the belt for presentation to the presser.

18. A belt tipping machine comprising a belt gripper adapted to hold the end portion of a belt, a presser, tape feeding means, a gripper slide and a tip attaching slide on which the gripper and presser respectively are mounted, means for reciprocating the slides to cause the presser to lay a strip of tape upon the end face of the belt, and a belt edge guide mounted for free sliding movement on the tip attaching slide and having provision for engaging the edge portions of the belt and guide it to the presser.

19. A belt tipping machine comprising a belt gripper for holding the end portion of a belt and having guide blocks embracing opposite edges of the belt, means for placing a strip of tape along the end face of the belt, a presser for pressing the tape on the end face of the belt and adapted to cooperate with the guide blocks to cut the tape, a reciprocating slide on which the presser is mounted, a presser guide for presenting the presser accurately to the guide blocks, and means for mounting the presser guide for free sliding movement on the slide.

20. A belt tipping machine comprising a belt gripper for holding the end portion of a belt and having guide blocks embracing opposite edges of the belt, means for placing a strip of tape along the end face of the belt, a presser for pressing the tape on the end face of the belt and adapted to enter the guide blocks to cut the tape, a reciprocating slide on which the presser is mounted, and a presser guide having provision for free sliding movement on the slide and provided with blocks embracing the lower end of the presser and adapted to be engaged by the guide blocks of the gripper as the presser enters the guide blocks.

21. A belt tipping machine comprising means for holding a belt, a presser adapted to engage with the end face of the belt to lay a tip thereon, means for actuating the presser, and means associated with the presser for engaging the belt prior to the engagement of the presser therewith to guide and stiffen the belt for presentation to the presser.

22. A belt tipping machine comprising means for holding a belt, a presser, means for moving the belt to engage its end face with the presser, a belt end guide associated with the presser and having a belt end positioning lug in the plane of the presser and plates on opposite sides thereof for engagement with the belt prior to engagement

thereof with the presser, and means for mounting the belt end guide for movement relative to the presser.

23. A belt tipping machine comprising a belt gripper adapted to receive the end portion of a belt, a presser adapted to engage with the end face of the belt, a reciprocating slide upon which the presser is mounted, a belt end guide carried by the slide and mounted for sliding movement thereon and adapted to engage with the end of the belt prior to the engagement of the presser therewith, and means for presenting a strip of tape in the path of the presser.

24. A belt tipping machine comprising a belt gripper having guide blocks adapted to closely engage the edges of a belt, a presser aligning with the belt and adapted to engage the end face thereof, means for reciprocating the presser, means for presenting a strip of tape in the path of the presser to be laid upon the end face of the belt, and means permitting the belt to be depressed through the gripper to cause engagement of the presser with the guide blocks of the gripper to cut the tape adjacent the edges of the belt.

25. A belt tipping machine comprising a belt gripper, a reciprocating slide, a presser on the slide in alignment with a belt received in the gripper, means for presenting a strip of tape in the path of the presser to be laid over the end face of the belt, a belt end guide adapted for movement with the presser to engage with and guide the end of the belt prior to the engagement of the presser with the belt, and means for yieldingly mounting the belt end guide to permit relative movement between the guide and the presser.

26. A belt tipping machine comprising a belt gripper adapted to receive the end portion of a belt, tip applying devices comprising a presser in alignment with the end of the belt, means for presenting a strip of tape between the end of the belt and the presser, and cams for reciprocating the gripper and the presser and adapted to bring the gripper and presser in engagement with the tape and to continue the movement of the gripper relative to the presser to lay the tape over the end face of the belt.

27. A belt tipping machine comprising a belt gripper having guide blocks adapted to engage the edges of the belt with the end portion of the belt projecting therethrough, a presser in alignment with the belt and adapted to enter the guide blocks, means for presenting a strip of tape between the presser and the end of the belt, a cam for reciprocating the presser to bring it into engagement with the tape, a cam for reciprocating the gripper to cause the end of the belt to engage with the tape and to continue the movement of the gripper to per-

mit the tape to be laid over the end of the belt and to cause the belt to be depressed through the guide blocks whereby the presser cuts the tape against the guide blocks and adjacent to the edges of the belt.

28. A belt tipping machine comprising a gripper slide, a tip applying slide, a gripper carried by the gripper slide and adapted to receive a belt with the end portion thereof projecting above the gripper, a presser attached to the tip applying slide, a belt end guide yieldingly mounted on the tip applying slide, means for presenting a strip of tape between the end of the belt and the presser, means for reciprocating the tip applying slide to bring the presser substantially into engagement with the tape, means for reciprocating the gripper slide to cause the end of the belt to engage with the belt end guide and to continue the movement of the end of the belt relative to the presser, and guide blocks on the gripper conforming to the shape of the belt and adapted to receive the presser therein to cut the tape adjacent the edges of the belt.

29. A tip applying machine comprising a fabric gripping device, pressing means adapted to engage with the end face of the fabric, reciprocating means for feeding a strip of tape between the end of the fabric and the presser, means for moving the pressing means toward the end of the fabric, and means for maintaining the fabric against flexure when the pressing means is moved toward the fabric.

30. A tip applying machine comprising a gripper adapted to receive a piece of fabric, a presser adapted to engage with the end face of the fabric, reciprocating means for reciprocating the gripper and presser toward each other, and reciprocating means for feeding a strip of tape across the path of the gripper.

31. A tip applying machine comprising a gripper for holding a piece of fabric, a presser adapted to apply a tip to the end face of the fabric, reciprocating means moving across the path of the presser for gripping a strip of tape and feeding it in position to be engaged by the end face of the fabric, and means for reciprocating the gripper and the presser toward each other to cause the tape to be attached to the fabric.

32. A belt tipping machine comprising a belt gripper, a presser adapted to apply a tip to the end of the belt, the gripper and presser being movable relatively to each other, reciprocating means moving between the gripper and the presser for gripping a strip of tape and feeding it in position to be engaged by the end face of the belt, and means for presenting the tape to the feeding means.

33. A belt tipping machine comprising a belt gripper, a presser, tape holding de-

vices engaging opposite sides of a strip of tape, feeding fingers having gripping devices adapted to engage with the tape presented by the holding devices, means for reciprocating the feeding fingers to feed the tape between the belt gripper and presser, means for separating the gripping devices of the feeding fingers to permit them to pass over the holding devices, and means for opening the holding devices to permit the feeding fingers to pass therethrough to feed the tape.

34. A belt tipping machine comprising a belt gripper adapted to receive a belt having a pointed end, a presser adapted to engage with the end face of the belt and having inclined surfaces conforming to the end of the belt, means for feeding a strip of tape between the end of the belt and the presser comprising feeding fingers having rolls adapted to engage with the tape, and means for preventing rotation of the rolls on the feeding movement of the fingers having provision for permitting rotation thereof when the presser engages with the end of the belt.

35. A belt tipping machine comprising a belt gripper adapted to receive a belt having a pointed end, a presser adapted to engage with the pointed end of the belt, a tape roll, reciprocating feeding fingers, means for presenting the tape from the tape rolls to the feeding fingers, gripping rolls on the feeding fingers, means for preventing rotation of the gripping rolls upon a feeding movement of the fingers having provision for permitting rotation of the rolls when the presser engages with the end of the belt to relieve the tension on the tape upon such engagement of the presser with the belt.

36. A belt tipping machine comprising a belt gripper adapted to receive the end portion of a belt, a presser adapted to engage with the end of the belt, tape feeding fingers for feeding a strip of tape between the end of the belt and the presser, gripping rolls on the feeding fingers for engagement with the tape, a ratchet cooperating with the rolls, a pawl engaging with the ratchet for preventing rotation of the rolls upon a feeding movement of the fingers, and means engaging with the ratchet for rotating the rolls to discharge the end of the tape when the fingers are moved in the opposite direction.

37. A belt tipping machine comprising belt holding means, means for pressing a tip upon the end of a belt, tape feeding rolls for feeding a strip of tape between the holding means and the pressing means, reciprocating fingers on which the rolls are mounted, and means for preventing rotation of the rolls on the feeding movement of the fingers and having provision for permitting rotation in the reverse direction.

38. A belt tipping machine comprising belt holding means, means for pressing a tip upon the end of a belt, tape feeding rolls

for feeding a strip of tape between the holding means and the pressing means, reciprocating fingers on which the rolls are mounted, a ratchet co-operating with the rolls, a pawl engaging with the ratchet for preventing rotation of the rolls upon a feeding movement of the fingers, and a stationary rack cooperating with the ratchet for rotating the rolls to discharge the end of the tape when the fingers are moved in the opposite direction.

39. A belt tipping machine comprising means for applying a tip of tape to the end face of a belt, and tape feeding means including tape engaging rolls, feeding fingers upon which the rolls are mounted, means for reciprocating the fingers, means for presenting the tape to the rolls, and means for increasing the pressure between the rolls on a feeding movement of the fingers.

40. A belt tipping machine comprising means for applying a tip of tape to the end face of the belt, and tape feeding means including tape engaging rolls, feeding fingers upon which the rolls are mounted, a cross slide on which the feeding fingers are pivoted, connections between the feeding fingers, means engaging one of the feeding fingers for varying the pressure between them, means for presenting the tape to the rolls, means for reciprocating the slide, and cam means operating on the pressure varying means for increasing the pressure between the rolls on a feeding movement of the fingers.

41. A belt tipping machine comprising means for applying a tip of tape to the end face of a belt, tape feeding fingers, a slide on which the fingers are mounted, gearing connections between the fingers, means for reciprocating the slide, separating rollers engaging one of the fingers, and means for actuating the separating rollers to separate the fingers prior to engagement thereof with the tape and to apply increased pressure between the fingers upon a feeding movement of the tape.

42. A belt tipping machine comprising means for applying a strip of tape to the end face of a belt, feeding fingers for feeding the tape for presentation to the tip applying means, a slide on which the fingers are mounted, gearing connections between the fingers, separating rollers cooperating with the fingers, presenting rollers for presenting the tape to the feeding fingers, a bracket on which the separating rollers are mounted, means for actuating the separating rollers to separate the fingers and close them upon the tape presented by the presenting rollers, and yielding means for applying an increased pressure to the fingers on a feeding movement of the fingers.

43. A belt tipping machine comprising belt holding means, a presser, a tape drum,

feeding fingers for drawing tape from the tape drum in position to be engaged by the presser, tensioning rolls to which the tape leads from the tape drum, tape presenting rolls for presenting the tape to the feeding fingers, tape feeding rolls mounted on the feeding fingers, means for reciprocating the feeding fingers to cause the tape to be engaged by the feeding rolls at a point between the tension rolls and the presenting rolls, means for separating the feeding fingers to clear the presenting rolls, and means for separating the presenting rolls to permit the feeding rolls to pass therethrough on a feeding movement of the fingers.

44. A belt tipping machine comprising belt holding means, a presser, a tape drum, two pairs of rolls through which the tape leads from the tape drum, a pair of feeding fingers, a slide upon which the fingers are mounted, means for reciprocating the slide to cause the fingers to engage the tape between the two pairs of rolls and to feed it in position to be engaged by the presser, means for separating the fingers to clear the rolls prior to engagement of the fingers with the tape, means for applying a spring pressure to the fingers to grip the tape upon the feeding movement, and means for relieving the spring pressure on completion of the feeding movement.

45. A belt tipping machine comprising a belt gripper adapted to hold the end portion of a pointed belt, a presser cooperating with the pointed end of the belt for laying a strip of tape thereon, a tape drum, tape feeding means, presenting rolls through which the tape leads from the feeding drum to be presented to the tape feeding means, and means for moving the tape drum upon engagement of the presser with the belt to permit free drawing of the tape through the rolls.

46. A belt tipping machine comprising a belt gripper adapted to hold the end portion of a pointed belt, a presser cooperating with the pointed end of the belt for laying a strip of tape thereon, a tape drum, tape feeding means, presenting rolls through which the tape leads from the feeding drum to be presented to the tape feeding means, an arm pivoted to the frame of the machine and having the tape drum mounted thereon, and means cooperating with the arm during the tip applying operation for moving the tape drum to slacken the tape and permit it to draw freely through the presenting rolls.

47. A belt tipping machine comprising belt holding means, a presser adapted to engage with and conform to the pointed end of a belt presented by the belt holding means to lay a strip of tape on the end of the belt, means for reciprocating the belt holding means and the presser to cause engagement of the presser with the end face of the belt,

a bell crank lever pivoted on the machine, a tape drum mounted on one arm of the bell crank lever, a pin on the belt holding means to engage with the other arm of the bell crank lever to move the tape drum and slacken the tape during the tip applying operation, tape presenting rolls through which

the tape leads from the drum, and tape feeding means adapted to receive the tape presented by the rolls and feed it in position 10 to be engaged by the presser.

In testimony whereof I have signed my name to this specification.

CARL J. LANDIN.
